UNITED STATES PATENT OFFICE.

CLARENCE D. PERRINE, OF CLEVELAND, OHIO.

GARMENT SUPPORTING AND DISPLAYING DEVICE.

Application filed April 12, 1918. Serial No. 228,101.

To all whom it may concern:

Be it known that I, CLARENCE D. PERRINE, a citizen of the United States, and a resident of Cleveland, in the county of Cuyahoga and State of Ohio, have invented an improvement in Garment Supporting and Displaying Devices, of which the following is a specification.

This invention relates to garment supports, and more particularly to supports for upper garments. One of the objects thereof is to provide a simple and practical device of the above nature adapted to securely and effectively support a garment. Another object is to provide a device of the above type, of compact construction and adapted for convenient manipulation. Another object is to provide a device of the above type in which a garment may be conveniently and effectively displayed for sale. Other objects will be in part obvious and in part pointed out hereinafter.

The invention accordingly consists in the features of construction, combinations of elements and arrangement of parts which will be exemplified in the structure herein-after described and the scope of the application of which will be indicated in the following claims.

In the accompanying drawing, in which is shown one of various possible embodiments of this invention,

Figure 1 is a front elevation thereof, showing the same in dotted lines in an alternative position.

Figure 2 is a side elevation of the parts shown in Figure 1; and

Figure 3 is a view similar to Figure 2 showing the parts in another position.

Similar reference characters refer to similar parts throughout the several views of the drawings.

As conducive to a clearer understanding of certain features of this invention, it may be noted that it is often desirable to support garments and particularly under garments compactly arranged as in sales rooms and yet have them readily exhibited in proper form to display their shape to good advantage. It is also highly desirable that the garments may be readily and conveniently displayed in order that a succession of such garments may be exhibited with little loss of time.

The attainment of the above advantage 55 without extensive or complicated apparatus is among the dominant aims of this invention.

Referring now to Figure 1 of the accompanying drawings, there is shown a curved 60 shoulder supporting member 10 which may well be formed of wood. Rigidly secured to this member as by the staples 11 at each end is a substantially rectangular frame 12 formed of stiff wire or small steel rods. 65

Mounted upon the upright members of this frame 12 in slidable relation as by means of the eyes 13, is a cross rod 14 which is given a double turn at the center to provide a double eye 15. Extending through this eye 15 is an upright rod 16 headed over at its lower end and provided with a washer 17 against which the eye rests. This rod 16 is provided with an acute double bend 18 and at a point upwardly spaced therefrom. 75 a sharp bend 19 against which the supporting member 10 normally rests. Above the bend 19, rod 16 passes through a slot 20 formed in the member 10 and thence upwardly to form the hook 21 by which the 80 device is supported as upon a suitable rod 22. It is to be understood that a number of these devices may be supported on a single rod 22 normally lying transverse to the rod. 75

Stretched between the rod 14 and the 85 upper rod 23 of the frame 12 which is forwardly displaced as indicated at 24 in Figure 2 of the drawings, are a number of flat springs 25, each of which embraces at its opposite ends the rods 14 and 23 respectively. The eyes 26 by which the latter connections are made, are formed by merely bending over the ends of the springs so as securely to hold the springs in place and yet permit them to turn with respect to the rods. 90 It may be noted that the springs are tempered in such form that they tend to bow, or spring forwardly with respect to the device as a whole, assuming the view shown in Figure 1 to be a front elevation. 95

In the use of the device, assuming that a garment is supported thereon, when it is desired to extend the front of the garment for display purposes, or better to support it, it is first slid along rod 22 into a position 105 in which it is spaced from the adjacent devices. It is then swung at right angles to its normal position which brings it into sub-

stantial parallelism with the supporting rod. This action brings the bend 19 into registry with slot 20 and the weight of the garment or action of the springs, or both, immediately causes the support 10 to drop downwardly to the double bend 18 as shown in Figure 3 of the drawings. As this action takes place, the rod 14 is moved upwardly with respect to the frame 12 and the several springs 25 are bowed outwardly and forwardly, as indicated in Figure 3. The breast portion of the garment is thus distended and it is thus held in a position in which it is displayed to advantage. By a simple reversal of the above steps, the support 10 is lifted above the bend or shoulder 19 and thereupon turned into the position shown in Figure 1, the support then being returned to its normal flat position.

It is to be understood that although the device is best suited for use as above set forth, it nevertheless is well adapted for employment as an ordinary support. It is extremely compact in the position shown in Figure 2, and when extended, as shown in Figure 3, it forms an excellent support for the garment.

It will thus be seen that there is provided apparatus in which the several objects of this invention are attained by simple and inexpensive means, and that the apparatus is well suited to meet the requirements of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

I claim as my invention:

1. In a garment-supporting device, in combination, a plurality of relatively movable supporting members mounted to form a collapsible supporting frame for the upper portion of a garment, and a device by which said frame is suspended adapted to turn relatively thereto and lock said members in position by its turning movement.
2. In a garment-supporting device, in combination, a supporting member, means connected with said supporting member adapted upon actuation to expand the garment, and a member adapted to suspend the device and to actuate said expanding means, said last member being rendered operative

by turning said first member with respect thereto about its axis.

3. In a garment-supporting device, in combination, a main supporting member, a member by which the device is suspended, a plurality of springs each held at one end against bodily movement, means comprising a lower member controlled from said second member adapted simultaneously to force the opposite ends of said springs toward the first-mentioned ends thereof and means adapted to guide the ends of said lower member.

4. In a garment-supporting device, in combination, a main supporting member of curved form, an upright member having a portion adapted to make connection with a stationary support and extending past said first member in guided relation thereto, a plurality of substantially upright spring members having their upper ends held against bodily movement, a connection between said upright member and the lower ends of said springs and guiding means for said connection.

5. In a garment-supporting device, in combination, a main supporting member of curved form, an upright member having a portion adapted to make connection with a stationary support and extending past said first member in guided relation thereto, a plurality of substantially upright spring members having their upper ends held against bodily movement, a connection between said upright member and the lower ends of said springs, said connection comprising a member to which said upright member is secured, and guides for the ends thereof.

6. In a garment-supporting device, in combination, a main supporting member of curved form, an upright member having a portion adapted to make connection with a stationary support and extending past said first member in guided relation thereto, a plurality of substantially upright spring members having their upper ends held against bodily movement, a connection between said upright member and the lower ends of said springs, and means controlled by twisting said upright member about a vertical axis for locking the parts in position.

In testimony whereof, I have signed my name to this specification this 10th day of April, 1918.

CLARENCE D. PERRINE.
